EDWARD M. BRACKETT AND FRED M. BRACKETT, OF TOPEKA, KANSAS.

INTERMITTENT FEEDING DEVICE.

Application filed May 20, 1928. Serial No. 110,579.

Our invention relates to an intermittent feeding device and particularly to such a device in which the intervals between feeding operations may be varied.

5 In certain machines such as stripping machines or other machines used for applying strips adjacent edges of sheets, the sheets are preferably fed into the machine intermittently and the interval between feeding operations is preferably varied in accordance with the size of sheet to be operated on. It is, accordingly, a purpose of our invention to provide feeding means of the above mentioned character in which the period between feeding 10 operations can be varied and to provide an improved clutch mechanism whereby such a feeding mechanism can be intermittently operated and the period between the beginning of each feeding operation and the succeeding feeding operation can be varied by adjustment of said means associated with the clutch mechanism.

More particularly it is a purpose of our invention to provide feeding means comprising 15 a reciprocable member, means for moving said reciprocable member in a feeding direction through a predetermined distance, means for returning the member to a predetermined point, and means for adjusting the initiation 20 of movement in a feeding direction to vary the interval between feeding movements of the reciprocable member. The adjusting means preferably comprises a member rotating at a constant speed, which has a feed 25 movement-initiating member mounted to rotate therewith and means for adjusting the arc through which the rotatable members rotate together before initiating movement of the feeding means in a feeding direction. 30 Specifically, the rotatable member that initiates the feeding movement by actuating the clutch associated with a drive member to connect the reciprocable means with the drive member, is free to rotate independently of the 35 driven member, rotating at a substantially constant speed and is adapted to be connected therewith at such times and in such a manner as to vary the distance that the driven member 40 rotating at a constant speed and the member actuating the clutch to initiate the feeding movement rotate together.

It is a further purpose of the invention to provide new and improved clutch mechanism for obtaining the intermittent movement 45 whereby the reciprocable member is driven in one direction by being connected by the

clutch with a driving member and moved in the reverse direction by any suitable means for retracting the same to starting position, the clutch rotating with the rotatable member associated with the reciprocable member and said rotatable member and clutch member also rotating in the reverse direction with the reciprocable member when the same is retracted. 60

65 Other objects and advantages of the invention will appear as the description of the accompanying drawings proceeds. However, we desire to have it distinctly understood that we do not intend to limit ourselves to the exact details shown or described, but that we intend to include as part of our invention all such obvious changes and modifications of parts as would occur to a person skilled in this art and as would fall within 70 the scope of the claims. 75

In the drawings:

Fig. 1 is a perspective view of a stripping machine embodying our improved feeding means. 80

Fig. 2 is a fragmentary plan view, partly broken away, thereof.

Fig. 3 is a fragmentary section taken on the line 3—3, Fig. 1.

Fig. 4 is a view partly in section and partly in elevation of the adjusting member and dial associated therewith. 85

Fig. 5 is a perspective view, with one of the bearings removed, of the improved clutch and clutch actuating mechanism used in conjunction with our improved feeding device. 90

Fig. 6 is a section taken on the line 6—6 of Fig. 7.

Fig. 7 is a longitudinal sectional view of the clutch mechanism and clutch actuating member. 95

Fig. 8 is a section taken on the line 8—8 of Fig. 7.

Fig. 9 is a perspective view of the rotatable member reciprocating the feeding means and the cam associated therewith. 100

Fig. 10 is a section taken on the line 10—10 of Fig. 7, showing the clutch in an unlatched position.

Fig. 11 is a similar view, showing the clutch in a latched position. 105

Fig. 12 is a perspective view of certain portions of the clutch mechanism, separated, associated with the clutch actuating means.

Fig. 13 is a fragmentary, longitudinal, 110 sectional view thereof on an enlarged scale, and

Fig. 14 is a perspective view of the driving clutch operating means disassembled from the clutch.

Referring in detail to the drawings:

- 5 Our improved feeding mechanism is shown as being applied to a machine 10 which may be a stripping machine, that is, a machine for applying strips of binding material to sheets of paper or similar sheet material, to 10 connect the same together. In a machine of this character the sheets are placed in feeding channels 11 provided between the guides 12 and the slotted bottom members 13 and in front of the fingers 14 operating in the slots 15 so that said fingers 14 in moving to the left as shown in Fig. 1, will feed the sheets in pairs into the machine. While it is obvious that while sheets are referred to, any object whether in pairs or singly may be fed in 20 this manner, provided an intermittent feed is desired.

In the form of the invention shown the fingers 14 are mounted upon a transversely extending member 15 that is carried by a 25 head 16 slidably mounted upon the guide rod 17 depending from the brackets 18 which are mounted in any suitable manner upon the machine 10.

The member 16 is mounted to reciprocate 30 with a reciprocable rod-like member 19 that is preferably hollow as shown in Fig. 2, and which is provided with a suitable guide member 20 through which the same extends, the guide member being secured in any suitable 35 manner to the machine 10. A tension spring 21 is mounted within the bore of the member 19, being secured to a cross pin 22 or any other suitable means at one end thereof and having the other end thereof secured 40 in an eye 23 provided on one end of the elongated hook 24 having a hook portion 25 that is adapted to be anchored in a suitable opening in the machine 10 for holding the same in position, the machine 10 being provided 45 with an opening 26 in the framework thereof through which the spring 21 extends.

The rod-like member 19 is provided with a pair of ears 27 at the other end thereof to which the rack 28 is secured by means of a 50 pin or other securing member 29. Meshing with the rack 28 is a gear 30 which is mounted on a shaft 31 and is normally free to rotate thereon, a sprocket wheel 32 being mounted on said shaft to rotate therewith, a 55 sprocket chain 33 operating over said sprocket wheel and over the sprocket wheel 34.

The sprocket wheel 34 is mounted to rotate with a shaft 35 which is driven in a constant 60 direction and at substantially a constant speed in any suitable manner, a gear 36 being mounted on the shaft 31 to rotate therewith. The gear 36, referring now to Fig. 7, meshes with a gear 37 which is mounted to rotate 65 freely upon the shaft 38, the shaft 31 being

mounted in suitable bearings in the brackets 39 and 40 and the shaft 38 having a reduced portion 41 terminating in a threaded end 42 with which the nut 43 engages to clamp the same in position on the lower end of the 70 bracket 39.

Formed integrally with the gear 37 or so as to rotate therewith at all times, is a drum-like member 44 within which is mounted a split, expandable member 45 which is shown 75 more in detail in Fig. 12, the member 45 being provided with suitable circumferential grooves 46 and transverse grooves 47 to increase the resiliency thereof. A cam member 48 is also freely, rotatably mounted upon the 80 shaft 38 between the flange 49 thereon and the gear 37, the expandable member 45 being secured to the member 48 by any suitable securing means extending through the opening 50 in the enlargement 51 provided on the inner side of the expandable member 45. Thus the member 45 when not expanded will be stationary within the rotating gear 37 in the drum portion 44 thereof. The member 48 is provided with a cam or lug 52 projecting therefrom which has a slightly bevelled face 53, as will be clear from Fig. 11. The member 48 is further provided with a groove 54 therein, within which the flexible member 55 85 is mounted, one end of the flexible member 55 being secured in the groove by means of the securing pin 56, the other end of the flexible member having a tension spring 57 secured thereto, which is anchored to the machine in any desired manner as by securing 90 the same to a lug 58 as shown in Fig. 1. Thus the flexible member 55 and spring 57 will tend to rotate the member 48 in a counter-clockwise direction as indicated by the broken-lined arrow shown in Fig. 11. 100

The shaft 38 which is stationary, is also provided with a tubular end portion 59 within which is seated a compression spring 60 that bears against a cross pin 61 that is movable in the slot 62 provided in the hollow end 59 of the shaft and which secures the sleeve 63 to the shaft for sliding movement thereon but holding the same against rotation. The sleeve 63 bears against a roller 64 which has an axle 65 mounted between the bifurcations 66 in the end of the pin 67 that is adapted to slide through an opening 68 in the member 48, the member 48 being further provided with a concave recess 69 for receiving the roller 64. The pin 67 is furthermore provided with a cross bar or cross pin 70 that engages with the free ends of the levers 71, one of which is provided with a slot 72 through which the reduced shank 73 of the other lever extends, said levers being pivotally secured 115 together by means of the pivot member 74 and having right angular ends 75 which are adapted to pry the ends of the expandable member 45 apart as the free ends of the levers are spread by engagement of the cross pin 120 130

70 therewith. The levers are held in alignment with the cross pin due to the fact that the cross pin and said levers rest in a slot 76 provided in the member 48, whereby the 5 movements thereof are guided.

The sleeve 63 is provided with a flange 77 that seats in the groove 77' provided in the flanged stop collar 78 which is provided with a laterally extending stop finger 79 which 10 the lug 52 is adapted to engage to limit the rotative movement of the member 48 due to the action of the spring 57. The stop collar 78 is provided with a groove 80 for receiving a cable or other flexible member 81 which may 15 extend around the same any desired number of times to obtain the required amount of friction thereon so that the member 80 will move along with the cable 81 without slippage. The other end of the cable 81 extends 20 around a pulley or drum 82 formed on the hub of the adjusting member 83 which is provided with suitable graduations 84 on the surface thereof to indicate the position of the same and with a suitable knurled surface 84' 25 to facilitate rotating the same. The member 83 is mounted upon a bolt-like member 85 carried by the bracket 86 depending from the machine 10, which is provided with a clamping member 87 having a handle 88 30 whereby the adjusting means can be clamped in any desired adjusted position. Thus by actuating the member 83, the stop finger 79 can be moved to any desired position around the shaft 38 to obtain any required position 35 for the lug 52 within the requirements of the machine.

The sprocket wheel 32 is mounted upon a hub 89 provided on the clutch member 90 which is pinned to the shaft 31 by means of 40 the pin 91, the sprocket 32 being secured to the enlarged portion 92 of the clutch member 90 by means of the rivets 93. Thus the sprocket 32 and clutch member 90 are mounted to rotate together and with the shaft 31. The 45 clutch member 90 is made in the form of a drum, having a bore within which the expansible member 94 is mounted.

The expansible member 94 is made quite similar in construction to the member 45 50 and has the rectangular cam member 95 mounted in the space 96 between the ends thereof at the split therein, whereby the member 94 may be expanded, the same having a normal tendency to contract to such a size 55 that it will be out of engagement with the inner face of the drum formed on the member 90. The ends of the member 94 are enlarged as shown at 97 to provide bearing portions 60 for the cam member 95, the member 94 being mounted upon a pin 98 projecting from the gear 30 which extends through an opening in an inwardly extending ear on the member 94, corresponding to the opening 50 in the ear 51 of the clutch 45.

65 Suitable means for operating the clutch

comprising the members 94 and 90 is provided, and comprises a lever 101 having an aperture 99 receiving the pin 98 to pivot the lever, and which is provided with an opening 102 through which the pin 103 provided on the gear 30 extends to limit the movement of the lever 101, the pin being of considerably less diameter than the opening to permit play of the lever. The lever 101 is provided with a cam portion 104 with which the cam face 75 53 on the member 52 is adapted to engage, and with a lug or projection 105 with which the projection 52 is adapted to engage to move the lever 101 from the position shown in Fig. 10 to that shown in Fig. 11. The lever 101 80 is further provided with a locking projection 106 that is adapted to engage with a shoulder 108 on a latch 107 pivoted on a pin 107' on the gear 30 and engaging with the shoulder 108 formed on the latch 107, the latch being 85 provided with a coil spring 109 hooked through a suitable eye in the same and extending at its other end around a pin 110 on gear 30 so that the spring 109 tends to hold the latch 107 in engagement with the locking 90 projection 106 on the lever 101.

The lever 101 is provided with a rearward projection 111 which is bifurcated as shown in Fig. 14 and which has pivotally mounted therebetween on the pivot pin 112 95 a T-shaped arm 113, the transversely extending portion of which is provided with openings through which the rod-like members 114 slidably extend, the rod-like members 114 being provided with heads 115 between 100 which and said transversely extending portions of the member 113 the compression springs 116 are mounted. The members 114 are screw threadedly engaged in a cross head portion 117 on the pivotally mounted block 105 118 which is supported on a pivot pin 119 mounted between the bifurcated end portions 120 of the lever 121. The lever 121 is pivotally mounted upon a suitable pivot pin 122 projecting from the gear 30 and rigidly carries the cam member 95 thereon at the pivoted 110 end thereof.

It will accordingly be seen that when the lever 101 is swung to the position shown in Fig. 11, the lever 121 will be swung to the position shown in Fig. 11, causing the cam member 95 to move to such a position as to spread the expansible member 94, thus engaging the clutch member 94 with the clutch member 90 and causing the gear 30 to rotate with the 120 shaft 31. The rotation is in a counter-clockwise direction as shown in Figs. 1, 8, 10 and 11, causing the rack 28 to be moved to the left in Fig. 1. The rack 28 is provided with flanges 123 that engage in the undercut 125 grooves 124 provided with the detachable flange members 125 to guide the movements thereof. The gear 30 is provided with teeth 126 which extend only part of the distance around the same, a portion of the gear 127 130

- being blank, as will be clear from the drawings, and the provision of teeth around the entire gear being unnecessary as will be obvious as the description proceeds.
- 5 The latch member 107 is provided with an outwardly projecting ear 128 which engages with the stationary cam 129 provided on the framework of the machine after the gear 30 has rotated through a suitable arc to move 10 the rack the necessary distance to perform the feeding operation of the fingers 14 and when this occurs the latch 107 is swung around in a clockwise direction to disengage the projection 106 from the shoulder 108 and release the lever 101 which then swings around to the position shown in Fig. 10 due to the spring action of the member 94 tending to throw the cam 95 around to the position shown in Fig. 10.
- 15 When the expandible member 94 is released from the member 90 the gear 30 is free to revolve on the shaft 31 and is rotated in a clockwise direction by the action of the spring 21 which moves the rack 28 back until the 20 end of the member 19 engages with the wall of the frame at the opening 26. This causes the member 94 and the clutch actuating mechanism actuated by the lever 101 to rotate as a whole around the shaft 31, bringing the member 105 back to the position shown in Fig. 10 when it is in position to be engaged by the member 52. Mounted on the gear 30 to rotate therewith is a cam member 130 which has the low portion 131 and the high 25 portion 132. The cam member may be formed integrally with the gear or made so as to rotate therewith in any other suitable manner. A pawl 133 is mounted on the frame of the machine 10 in such a position that the 30 same may be engaged by the high portion 132 of the cam to swing the same in a clockwise direction, as viewed in Fig. 8, around its pivot 134. The rear end of the pawl has pivotally connected therewith a link or rod 35 135 which passes through a flattened ear 136 on the end of the crank 137. Pinned on the transversely extending portion 138 of the crank 137 is a yoke 139 having pins 140 thereon projecting into the groove 141 provided on the collar 63, the crank portion 138 extending through ears 142 projecting downwardly and laterally from the bracket 143 secured to the hollow end 59 of the shaft 38 by means of the bolt 144, the bolt 144 also 40 55 acting to compress the spring 60 in the bore of the hollow portion 59 of the shaft 38. Thus when the pawl is swung downwardly on the bevelled end thereof or clockwise, the rear end thereof will move upwardly, pulling upwardly on the rod 135 and swinging the crank 137 around so as to swing the yoke outwardly toward the bracket 143, thus causing the member 77 to disengage the roller and allowing the levers 71 to move toward each 60 65 other, thus swinging the same around to the position shown in Fig. 12, whereupon the member 45 contracts to disengage the member 48 from the gear 37. The cam reaches such a position that the high portion 132 thereof engages with the pawl 133 after the member 52 has engaged with the projection 105. As soon as this occurs, the spring 57 will return the member 48 to the position shown in Fig. 10, with the projection 52 engaging with the stop arm 79.
- 75 A compression spring 145 surrounds the rod 135 and is mounted between the washer 146 engaging against the cotter pin 147 on the rod and the flat end 136 of the lever 137 to compensate for any variation in the distance between the flattened end 136 of the member 137 and the opening in the pawl 133 receiving the hooked end of the rod 135 when the pawl returns to its original position and the member 63 moves toward the roller 64 under influence of the spring 60, whereupon the clutch member 45 will be expanded to cause the member 48 to rotate with the gear 37.
- 80 As the gear 37 rotates at substantially constant speed, the position of the stop member 79 will determine the interval that is consumed in the movement of the lug 52 on the member 48 from its retracted position to the position when it engages with the projection 105 on the lever 101. The end of the cam portion 132 is reached at such a time that the projection 128 on the latch 107 will have been engaged by the stationary cam 129 prior to the time when the member 52 reaches 85 a position to engage with the projection 105 on the lever 101, and accordingly the gear 30 will always have been returned to the position shown in Fig. 10 before the projection 52 has reached the position to actuate the 90 lever 101 to connect the clutch members 90 and 94 together to rotate as a unit. As the position of the stop member 79 is determined by adjustment of the member 83, the interval 95 between the times when the rotation of the gear 30 with the shaft 31 and accordingly the feeding movements of the members 14 are 100 begun, may be adjusted by adjustment of the member 83 by means of the dial 84 thereon. Thus, while the speed of feeding and the 105 speed at which return of the feeding means takes place is not varied, the interval between feeding movements is varied by adjustment of the member 83.
- 110 115 In order to cushion the shock of the member 19 engaging with the frame of the machine under the action of the spring 21, a bracket 149 is provided on the member 19 which is connected through the link 150 in the lever 151 with a fluid check member 152 120 which operates in a similar manner to a door check or similar device to slow down and cushion the movement of the member 19 as it reaches the end thereof.
- 125 It will be obvious that if it is desired to 130

halt the feeding action of the feeding device, all that is necessary is to unhook the hook 25, releasing the tension on the spring 21. As the clutch member controlling the feeding operation will then stop with the latch released and will not be returned to such a position that the parts can be reset to again connect the clutch members to rotate together, the feeding operation will stop.

10 Assuming the parts to be constructed and assembled as described, the operation is as follows:

When power is applied to the drive shaft 35, the shaft 31 is rotated counter-clockwise, 15 carrying the gear 36 with it and rotating the gear 37 clockwise. There being a normal tendency of the clutch 45 to engage the drum 44 because of the tension of spring 60 urging the sleeve 63 against the roller on the pin 67 20 to spread the arms 71 and open the clutch 45 to gripping relation with the drum, the drum 44 is rotated clockwise synchronously with the gear 37. Rotation of the drum carries its lug 52 to engagement with the lug 105 on the lever 101 pivotally mounted on the gear wheel 25 30, which latter is freely rotatable on the shaft 31; rocking the levers 101 and 121 to cam the expansible clutch 94 to locking engagement with the clutch member 90 fixed to the shaft 31, so that the clutch 90 and gear wheel 30 will rotate counter-clockwise with the shaft 31, the lever 101 then being held in 35 position for retaining the locking relation of the clutch members by the latch 107. Consequently, while the parts are in this relation, the gear wheel 30 operates on the rack 28 to draw the rack toward the left, in Fig. 1, and against the tension of the spring 21.

Immediately upon initiation of the driving 40 travel of gear 30, the cam 132 on gear 30 engages the pawl 133, rocking the pawl, raising the rod 135, rocking the crank 137 and shifting the sleeve 63 to relieve pressure on the clutch 45 and releasing the cam member 48 so that movement of the gear wheel 37 is 45 interrupted. Immediately upon its release, the cam member 48 is returned counter-clockwise until its lug 52 engages the stop finger 79 on the collar 78. The gear 30 continues to 50 revolve until the extension 128 of latch 107 engages the fixed cam 129 on the frame of the machine, rocking the latch to release lever 121 which is then automatically returned to initial position, releasing the 55 clutch 94.

The cam 132 is of sufficient extent to hold the pawl and retain the clutch 45 out of engagement with drum 44 until the gear mechanism has completed an active phase. At the 60 completion of such phase, the extension 128 engages the fixed cam 129 on the machine crank, rocking the latch to release lever 101 and gear wheel 30 so that the gear wheel 30 again becomes inactive.

65 Just prior to the release of gear wheel 30

the cam 132 rides off of the pawl 133, releasing the crank 137 so that the clutch 94 may again become active to connect the gear wheels through the lever mechanism heretofore described, so that the operation 70 may be repeated, the rack 28 having been returned to initial position by the spring 121 immediately upon release of the gear wheel 30, so that it may again be reciprocated through the operation of the gear mechanism. 75

By adjustment of the stop finger 79 through the cable 81 from the adjusting member 83, the extent of reciprocation of the rack may be controlled to limit its travel to an extent sufficient for feeding sheets of different dimensions. 80

What we claim and desire to secure by Letters Patent is:

1. In a device of the character described, a rotatable member for moving a reciprocable 85 member in one direction, means for intermittently rotating said rotatable member, comprising a constantly rotating member, a clutch device adapted to connect said constantly rotating member with said rotatable member, means actuating said clutch to connect said rotatable member with said constantly rotating member, means actuating said clutch to disconnect said members and means for adjusting said first mentioned 90 actuating means to vary the interval between the actuations of said clutch to connect said rotatable member with the constantly rotating member. 95

2. In a device of the character described, 100 feeding means comprising a rotatable member, and means for intermittently rotating said rotatable member in opposite directions, comprising a constantly rotating member for rotating the same in one direction, returning means for rotating the same in the opposite direction, a clutch device adapted to connect said constantly rotating member with said rotatable member, means actuating said clutch to connect said members, means actuating said clutch to disconnect said members and means for adjusting said first mentioned 105 actuating means to vary the interval between the actuations of said clutch to connect said members. 110

3. In a device of the character described, 115 feeding means comprising a rotatable member, and means for intermittently rotating said rotatable member in opposite directions, comprising a constantly rotating member for 120 rotating the same in one direction, returning means for rotating the same in the opposite direction, a clutch device adapted to connect said constantly rotating member with said rotatable member, means actuating said clutch to connect said members, means actuating said clutch to disconnect said members and means for adjusting said first mentioned 125 actuating means to vary the interval between the actuations of said clutch to connect said 130 members.

members, said first mentioned actuating means comprising a driving member rotating at a substantially constant speed, a rotatable clutch actuating member and means connecting said actuating member with said driving member to rotate the same in unison.

4. In a device of the character described, feeding means comprising a rotatable member, and means for intermittently rotating said rotatable member in opposite directions, comprising a constantly rotating member for rotating the same in one direction, returning means for rotating the same in the opposite direction, a clutch device adapted to connect said constantly rotating member with said rotatable member, means actuating said clutch to connect said members, means actuating said clutch to disconnect said members, said first mentioned actuating means comprising a driving member rotating at a substantially constant speed, a rotatable clutch actuating member and means connecting said actuating member with said driving member to rotate the same in unison and disconnecting said actuating member from said driving member, means to retract said actuating member and adjustable means for limiting the retractile movement of said actuating member to adjust the interval between actuations of the clutch to connect said constantly rotating member with said intermittently rotating member.

5. In a device of the character described, a rotatable driving member, a member to be intermittently rotated thereby in one direction, means for rotating said last member in the opposite direction when free of said driving member, clutch means actuated by said driving member to connect said members together to rotate in unison and means for adjusting the intervals between connecting actuations of said clutch means.

6. In a device of the character described, a rotatable driving member, a member to be intermittently rotated thereby in one direction, means for rotating said last member in the opposite direction when free of said driving member, clutch means actuated by said driving member to connect said members together to rotate in unison, fixed means actuating said clutch means to disconnect said members, and means for adjusting the interval between connecting actuations of said clutch means.

7. In a device of the character described, a rotatable driving member, a member to be intermittently rotated thereby in one direction, means for rotating said last member in the opposite direction when free of said driving member, clutch means actuated by said driving member to connect said members together to rotate in unison, and means for adjusting the interval between connecting actuations of said clutch means, said intermittently rotated member rotating through sub-

stantially the same arc for all adjustments of said last mentioned means.

8. In a device of the character described, means for moving a member in a feeding direction through a predetermined distance, means for adjusting the initiation of movement of said moving means in a feeding direction to vary the interval between feeding movements of said moving member, comprising a member rotating at substantially a constant speed, a feed movement initiating member rotatable therewith and means for adjusting the arc through which said rotatable members rotate together before said initiating member reaches feed movement initiating position.

9. In a device of the character described, feeding means comprising a reciprocable member, means for moving said member in a feeding direction through a predetermined distance, resilient means for returning said member to a predetermined point and means for adjusting the initiation of movement in a feeding direction to vary the interval between feeding movements of said reciprocable member.

10. In a device of the character described, feeding means comprising a reciprocable member moving a member in a feeding direction through a predetermined distance at substantially a constant speed, and means for adjusting the initiation of movement of said moving means in a feeding direction to vary the interval between feeding movements of said member, comprising a member rotating at substantially a constant speed, a feed movement initiating member rotatable therewith and means for adjusting the arc through which said rotatable members rotate together before said initiating member reaches feed movement initiating position.

11. In a device of the character described, a rotatable driving member, a member driven thereby to rotate substantially at a constant speed, an intermittently rotatable member, clutch means adapted to connect and disconnect said driving member with said intermittently rotatable member, means for retracting said intermittently rotatable member when disconnected from said driving member, a rotatable clutch actuating member adapted to rotate with said driven member and adjustable means determining the arc through which said actuating member rotates with said driven member before actuating said clutch to connect the intermittently rotatable member with said driving member.

12. In a device of the character described, a rotatable driving member, a member driven thereby to rotate substantially at a constant speed, an intermittently rotatable member, clutch means adapted to connect and disconnect said driving member with said intermittently rotatable member, means for retracting said intermittently rotatable member when

disconnected from said driving member, a rotatable clutch actuating member adapted to rotate with said driven member, positively operating means connecting and disconnecting 5 said actuating member and said driven member, means for reversely rotating said actuating member when disconnected from said driven member and adjustable means for limiting the reverse rotation thereof.

10 13. In a device of the character described, a rotatable driving member, a member driven thereby to rotate substantially at a constant speed, an intermittently rotatable member, clutch means adapted to connect and disconnect 15 said driving member with said intermittently rotatable member, said clutch means rotating with said intermittently rotatable member, means for rotating said intermittently rotatable member when disconnected 20 from said driving member, a rotatable clutch actuating member adapted to rotate with said driven member and adjustable means determining the arc through which said actuating member rotates with said driven member before 25 actuating said clutch to connect the intermittently rotatable member with said driving member.

14. In a device of the character described, a rotatable driving member, a member driven thereby to rotate substantially at a constant speed, an intermittently rotatable member, clutch means adapted to connect and disconnect 30 said driving member with said intermittently rotatable member, said clutch means rotating with said intermittently rotatable member, a member on said clutch means for moving the same to connecting position, a rotatable member movable into engagement therewith to actuate the same and means for 35 adjusting said rotatable member to determine the interval between connecting actuations of 40 said clutch means.

15. In a device of the character described, a rotatable driving member, a member driven thereby to rotate substantially at a constant speed, an intermittently rotatable member, clutch means adapted to connect and disconnect 45 said driving member with said intermittently rotatable member, said clutch means rotating with said intermittently rotatable member to its initial position.

member, a member on said clutch means for releasing the same, a member in the path of rotation thereof engaging therewith to actuate the same to release said clutch means, and means retracting said intermittently rotatable member to its initial position.

16. In a device of the character described, a rotatable driving member, a member driven thereby to rotate substantially at a constant speed, an intermittently rotatable member, clutch means adapted to connect and disconnect said driving member with said intermittently rotatable member, said clutch means rotating with said intermittently rotatable member, a member on said clutch means for 60 releasing the same, a member on said clutch means for moving the same to connecting position, a rotatable member having means movable into engagement therewith, and means retracting said intermittently rotatable member to its initial position with said member for moving the clutch means into connecting position in the path of the means on the last mentioned rotatable member.

17. In a device of the character described, a rotatable driving member, a member driven thereby to rotate substantially at a constant speed, an intermittently rotatable member, clutch means adapted to connect and disconnect 65 said driving member with said intermittently rotatable member, said clutch means rotating with said intermittently rotatable member, a member on said clutch means for releasing the same, a member on said clutch means for moving the same to connecting position, a rotatable member having means movable into engagement therewith, and means retracting said intermittently rotatable member to its initial position with said member for moving the clutch means into connecting position in the path of the means on the last mentioned rotatable member, said last mentioned rotatable member being adjustable to vary the interval between connecting actuations of said clutch means.
